UNITED STATES PATENT OFFICE.

MORLEY PUNSHON REYNOLDS, OF CLEVELAND, OHIO, ASSIGNOR TO THE W. S. TYLER COMPANY, OF CLEVELAND, OHIO, A CORPORATION OF OHIO.

CAR.

1,152,047.

Specification of Letters Patent. Patented Aug. 31, 1915.

Application filed April 24, 1914. Serial No. 834,252.

To all whom it may concern:

Be it known that I, MORLEY PUNSHON REYNOLDS, a citizen of the United States, and a resident of Cleveland, in the county 5 of Cuyahoga and State of Ohio, have invented a new and useful Improvement in Cars; and I do hereby declare the following to be a full, clear, and exact description thereof.

10 My invention relates to railway cars and particularly refers to the refrigerator type wherein ice chambers or bunkers are located in the ends of the same, although ordinary freight cars of the box design with the 15 proper and necessary ventilation may be arranged for similar purposes.

The object of my invention is to provide a cheap, simple and efficient form of buffer or shock absorber which can be applied to 20 the bulkheads of ice bunkers in refrigerator or other cars wherein the rigidity of the end wall or bulkhead will be eliminated and such bulkhead or wall provided with an auxiliary resilient wall made from flexible material in order that fragile articles or crates packed in the car and placed against such walls will not be broken during the course 25 of transit or during the shifting, starting and stopping of such car.

30 A further object of my invention is to provide a buffer or shock absorber device for use in cars wherein the end walls of the storage compartment will be resilient and will be formed of such material as will permit 35 of the air readily passing through the same into the interior of the car, thus not interfering with air circulation.

My invention consists, generally stated, in the novel arrangement, construction and 40 combination of parts as hereinafter more specifically set forth and described and particularly pointed out in the claims.

To enable others skilled in the art to which my invention appertains to construct 45 and use my improved buffer or shock absorber in ventilated box or refrigerator cars, I will describe the same more fully referring to the accompanying drawing in which—

50 Figure 1 is a partial longitudinal sectional view showing the buffer or shock absorber in position. Fig. 2 is a cross-sec-

tional view of the car showing the auxilliary wall broken away in a portion of the same.

Like symbols of reference herein indicate 55 like parts in each of the figures of the drawing.

In the approved styles of ice bunkers used in refrigerator cars at the present day, the bunker wall or bulkhead is composed of 60 very rigid material so that oftentimes when the cars are shifted in switching and bumped into other cars for the purpose of coupling, also the sudden stopping of trains by applying brakes, the commodities particularly if very fragile, such as cases of 65 eggs, are injured and broken and oftentimes great loss is sustained.

In my invention as shown by the drawing, 1 represents the floor of an ordinary refrigerator car, 2 the end wall, 3 the side walls and 4 the roof. Extending across the end of the car is my improved ice chamber bulkhead or partition *a* which is formed in the usual manner and properly secured in the 75 top of the car. This bulkhead consists of the inner and outer walls 5 and 6 and the inner wall extends down to the grid 7 upon which the ice 8 is adapted to rest. The outer wall 6 extends down to a position near the 80 floor of the car and is provided at the center with a small trap-door 9, while the upper end of said wall terminates in the heavy screen portion 10. This outer wall 6 is provided at suitable places with spring connecting members 11 for the purpose of receiving spiral springs 12, the outer ends of which are connected to the blocks or clips 13 on the inner side of the auxiliary wall 14. This wall 14 consists of the outer frame 15 with the cross 85 pieces 16 and the entire wall is covered with flexible material such as woven wire fabric 17 in order to decrease the rigidity of the same and make it substantially flexible and such wall extends to a point about even with 90 the level of the floor and is adapted to be movable thereon.

When fragile commodities such as eggs in cases are placed against the auxiliary wall 14 there will be less likelihood of the same being 100 broken during transit as ordinary vibrations, and even severe shocks will be absorbed by the spiral springs 12 between the wall 14 and outer wall 6.

Various modifications and changes in design and construction of my improved refrigerator cars may be resorted to without departing from the spirit of this invention 5 or sacrificing any of its advantages.

What I claim as my invention and desire to secure by Letters Patent is:—

1. A car provided with a transverse bulkhead, an auxiliary frame connecting with 10 said bulkhead and spaced therefrom, a flexible covering on said frame, and resilient means between said bulkhead and frame adapted to absorb shocks.
2. A car provided with a transverse bulkhead, an auxiliary frame connecting with 15 said bulkhead and spaced therefrom, a wire fabric covering on said frame, and spiral springs between said bulkhead and frame adapted to absorb shocks.
3. In a railway car, a transverse bulkhead including inner and outer spaced walls, said outer wall being rigid for a portion of its height and being flexible at its upper portion, an auxiliary frame, a flexible covering 20 extending over all of said frame, and yieldable means interposed between the frame and outer wall for absorbing shocks.

4. In a railway car, a transverse bulkhead including inner and outer main walls, said outer walls consisting of a rigid lower portion and a flexible upper portion, an auxiliary wall consisting of a frame and a flexible foraminous covering therefor, and yieldable means interposed between the outer main wall and the auxiliary wall for absorbing 30 shocks received by said auxiliary wall.

5. In a railway car, a transverse bulkhead including inner and outer main walls, said outer walls consisting of a rigid lower portion and a flexible upper portion, said rigid 35 and flexible portions being respectively fixed to the floor and ceiling of the car, an auxiliary wall consisting of a frame and a flexible foraminous covering therefor, and yieldable means interposed between the outer main 40 wall and the auxiliary wall for absorbing shocks received by said auxiliary wall.

In testimony whereof I the said MORLEY PUNSHON REYNOLDS have hereunto set my hand.

MORLEY PUNSHON REYNOLDS.
